INDUCTION COIL

David Pisarev, Bethlehem, Pa.

Application December 21, 1938, Serial No. 247,085

7 Claims. (Cl. 219—47)

This invention relates to new and useful improvements in induction coils, and more particularly to a novel induction coil which is particularly adapted for use in high frequency heating apparatus for treating susceptors disposed externally about the induction coil.

At the present time induction coils employed in high frequency furnaces of this type are generally of cylindrical or tapered shape, or otherwise conform to the contour of the article around it. It is desirable to employ a coil of this character in order that the coupling between the coil and article being heated may be uniformly maximum throughout the length of the coil. That is to say, since the coupling between the coil and the article being heated determines the heating action, and since the coupling at any point along the axial length of the coil depends upon the proximity of the coil at that point to the article, it is desirable to employ a coil which conforms to the contour of the article around it thus obtaining uniformly maximum coupling and consequent maximum heating throughout the length of the article.

It is characteristic of high frequency furnaces employing such a coil within a susceptor however, that the susceptor does not heat uniformly throughout its cross section due to the fact that the magnetic field does not penetrate sufficiently into the susceptor away or outwardly from the coil. When electromagnetic energy flows into the interior of a conducting means, its conversion into heat starts at the surface where it enters and diminishes at every point distant beyond the surface. Also this peripheral heating is not distributed uniformly along its length due to the fact that the strongest field is midway between the ends of the coil with the result that the conversion of energy diminishes markedly along the axial direction of the coil as the distance from the center outwardly toward the ends increases. For example, in a wheel hub having a cylindrical inside surface surrounding a cylindrical coil of about the same length, the greater part of the electromagnetic energy around the coil that is converted into heat in the inner cylindrical "skin" of the object is low in efficiency and distributed very unevenly along its length, and the fact that the ends of the object reside in a much less intense heating region of the coil is evidenced by the visible reddening of the cylindrical surface near the center when an object of considerable length is first heated, while the end portions of the object remain black for a considerable period becoming

red only after further heating. At any instant a portion of the object midway between its ends gives the appearance of a more intense redness than the ends, an indication of higher temperature. The efficiency of a heating device of this type is considerably low since the entire length of the article to be heated does not receive the full force or action of the flux or magnetic field induced. The result of this is, of course, that it requires operation of the furnace for a longer period of time than should be necessary to compensate for the time required to allow the smaller amount of heat in the ends to reach the desired temperature. In any instance, considerable heat is dissipated or lost by radiation and conduction from the object being heated, and this longer period of time required for operation of the furnace consequently results in an increase in such radiation and conduction losses. For "skin" hardening, excessive conduction into the interior of the article is undesirable.

By the present invention, this deficiency of coils of this type here involved is materially minimized and at the same time the advantages of such a coil are retained. This is accomplished by providing at the ends of the cylindrical type of coil inwardly converged or converging coil extensions which serve to direct the magnetic flux more obliquely to or more toward the surrounding article, thereby providing a better distribution of the magnetic flux and greater inductance while still maintaining the same good coupling within the central section of the coil. The converged or converging end construction causes a more rapid heating of the end portions of an object located externally around the central section of the coil and increases the control of heat distribution and uniformity of heating, as desired, along the length of the article to be heated, due to the increase in strength of the magnetic field induced therein which results in a more efficient heating apparatus. The distribution of the magnetic flux around this novel coil is considerably better than a coil without extensions since the shape of the coil follows more closely the path of the magnetic flux and reduces flux interthreading through the coil.

With the foregoing observations in mind, the principal object of the present invention is to provide an induction coil which is constructed and arranged to direct magnetic flux more obliquely to or more toward a susceptor located externally about the coil, and this and other objects of the invention, as well as the features and details of its construction and operation,

are hereinafter fully set forth and shown in the accompanying drawing, in which:

Figure 1 is a vertical section through an induction coil made according to this invention;

Figures 2 and 3 are diagrammatic illustrations showing modified arrangements of an induction coil embodying said invention;

Figure 4 is a diagrammatic view of a high frequency inductive heater or furnace embodying a coil made according to the present invention; and

Figure 5 is a vertical section of still another form of coil embodying said invention.

As pointed out above, the invention consists essentially in the construction of an induction coil to provide at its ends portions arranged in inwardly converging or offset relation in contrast to the conventional cylindrical type of coil. The flux or magnetic field thus set up externally of the coil is directed more obliquely to or more toward a susceptor placed thereabout, and referring to the drawing, an induction coil made according to the present invention may be composed of a continuous single layer or winding of relatively flat or round tubular wire wound to form a lower diverging portion A which terminates at its upper end in a central portion B of cylindrical shape, which in turn, terminates at its upper end in an inwardly converging portion C. In some cases it may be desired to have the central portion B of the coil conform to the cross-sectional shape of an irregular object placed thereabout to be heated and, therefore, it is understood that the invention embraces such modification.

The induction coil is preferably wound upon a suitable mandrel having a surface configuration which conforms approximately to the desired contour of the coil. The angles at which the opposite end sections A or C are disposed with respect to the central section B may be varied as desired to suit performance requirements, and the number of turns per unit of length in the same or other sections of the coil need not be uniform therein. Furthermore, the number of turns or coils of wire employed in the end portions A or C of the coil may vary as desired to provide any desired ratio between the number of turns or coils of wire in the said portions A or C and the central portion B and, of course, as the length of the said central portion B decreases or is decreased, the more critical or narrow will become the region of concentration of the magnetic field thereabout. The limiting case of this involves a coil such as that shown in Figure 5 of the drawing wherein the central section B''' is of minimum length or height having but a single turn. An arrangement such as this enables concentrated heating of a small length of a susceptor and at the same time, the advantages of a multiple turn coil are retained.

The induction coil contemplated by this invention is not restricted to the particular configuration or shape illustrated in Figure 1 of the drawing, and similar results are obtained, for example, by constructing an induction coil to provide at opposite ends of the central portion B' portions A' or C' which curve concavely inwardly and axially of the coil as shown in Figure 2 or as shown in Figure 3 wherein inwardly and axially curving convex portions A'' or C'', respectively, are provided at opposite ends of a central portion B''. Other forms and shapes

may, however, be employed with satisfactory results.

By directing the flux or magnetic field more toward the susceptor or article to be heated, a coil constructed in accordance with this invention may be employed to advantage to materially increase the efficiency of heat treating apparatus such as high frequency furnaces, one form of which is shown in Figure 4 of the drawing, and comprises an induction coil 3 suitably mounted within a susceptor 4 and spaced therefrom by suitable insulation indicated by reference numeral 5, although in some cases no insulation is needed or desirable.

As shown, the induction coil 3 comprises a plurality of turns of wire wound to the general shape or form shown in Figure 1 and consists of a central portion B and inwardly converging end portions A and C, a high frequency current being supplied to said coil 3 through the extremities of the end portions 6 and 7 thereof or at intermediate points as desired. For the purpose of cooling the coil, water or other cooling fluid may be passed through the tubular wire forming said coil through the openings afforded at the extremities of the end portions 6 and 7 or at intermediate points of the coil. Use of the coil 3 for heating purposes as described is confined essentially to the central portion thereof in order to obtain maximum coupling and consequently maximum heating of the susceptor, and so that the inwardly and axially converging end portions A and C thereof will function fully to direct the magnetic field more obliquely to and more toward the susceptor to be heated so that the entire length of the object may receive the full force or action of such flux or magnetic field. The heating efficiency and control of heat distribution of the coil is thus materially increased with the result that the length of time required to heat an object, the amount of power consumed, and equipment necessary are each substantially reduced. In some instances of use of the coil where it is desired to further aid in completion of the magnetic path through the coil, it may be desirable to place steel laminæ within said coil.

While my description of the invention has been confined to the embodiment or adaptation thereof to high frequency induction heaters and furnaces, it will be obvious, of course that the use of said invention is not limited to a device of that nature but may be employed to advantage in any instance where it is desired to obtain a maximum magnetic field strength in a susceptor about the coil and where the length of the central portion is decreased the more narrow or critical is the region of concentration of the magnetic field thereabout.

I claim:

1. An inductive heating device comprising an induction coil consisting of a winding of wire having a central heating portion of wire arranged for disposition within a susceptor to be heated, and end portions of wire arranged in inwardly offset relation with respect to said central portion.

2. An inductive heating device comprising an induction coil consisting of a winding of wire having a central substantially cylindrical portion arranged for disposition within an object to be heated, and end portions leading from the ends of said central cylindrical portion and offset with respect thereto in a direction toward the axis of the coil, said end portions constituting means for

directing the lines of flux more toward the object to be heated.

3. An inductive heating device comprising an induction coil consisting of a winding of wire having a substantially straight-sided heating portion arranged for disposition within a susceptor to be heated, and end portions offset inwardly toward the axis with respect to the straight-sided portion to control the distribution of heat in the susceptor along the axial direction thereof.

4. An inductive heating device comprising an induction coil consisting of a winding of wire having a central substantially cylindrical portion consisting of at least one turn of the wire arranged for disposition within a susceptor to be heated, and end portions offset inwardly with respect to the central portion, said end portions constituting means for directing the magnetic flux more toward the susceptor.

5. An inductive heating device comprising an induction coil consisting of a winding of wire having a central substantially straight-sided portion arranged for disposition within a susceptor to be heated and curving end portions leading away

from the ends of said central portion and offset with respect thereto in a direction toward the axis of the coil.

6. An inductive heating device comprising an induction coil consisting of a winding of wire having a central heating portion conforming substantially to the internal contour of and arranged for disposition within a susceptor to be heated and end portions arranged in inwardly offset relation with respect to the central portion, said end portions constituting means for controlling the distribution of heat in the susceptor along the axial direction thereof.

7. An inductive heating device comprising an induction coil consisting of a winding of wire having a central heating portion conforming substantially to the internal contour of and arranged for disposition within a susceptor to be heated, end portions arranged in inwardly offset relation with respect to the central portion, and iron laminæ disposed within the coil for the purpose of improving and controlling the magnetic path in the coil.
